UNITED STATES PATENT OFFICE.

BRODIE J. RICHARDSON AND CLAIRE S. BARBER, OF WATERBURY, CONNECTICUT.

HAND-BAG LOCK.

Application filed June 22, 1920. Serial No. 390,746.

To all whom it may concern:

Be it known that we, BRODIE J. RICHARDSON and CLAIRE S. BARBER, citizens of the United States, and residents, respectively, of Waterbury, in the county of New Haven and State of Connecticut, have jointly invented certain new and useful Improvements in Hand-Bag Locks, which improvements are fully set forth in the following specification.

This invention relates to improvements in devices of that class available conjunctively with a suitable tenoned hasp for locking together the customary hinged frame-sections of a hand-bag or the like, such devices being well-designed hand-bag locks.

The object of this invention is to provide a lock of the character above indicated, which shall be simple and comparatively inexpensive as regards its construction; which shall embody certain novel features of construction whereby the tumbler of the device may be manipulated for bolt-controlling purposes, either directly by finger-pressure or indirectly through the medium of a key, at the option of the user; which shall be durable, efficient and reliable in practical service; and which shall possess certain well-defined advantages over prior analogous constructions.

The invention consists in the novel combinations, details and parts, hereinafter more specifically referred to and set forth in the appended claims, and whereby the attainment of the foregoing object is rendered practicable.

The invention is clearly illustrated in the accompanying drawing, wherein:

Fig. 1 is a top plan view of a hand-bag lock embodying our said improvements, the depressible finger-piece being shown partly in horizontal section and the top segment of the housing being partly removed.

Fig. 2 is a rear elevation of same, the depressible finger-piece being shown partly in central, vertical section.

Fig. 3 is a central-vertical transverse section, as along the dotted line 3—3 of Fig. 2.

Fig. 4 is a detail, transverse section, as along the dotted line 4—4 of Fig. 2.

Fig. 5 is a view showing in perspective and detached the laterally shiftable tumbler made use of.

Fig. 6 is a detail perspective view showing more particularly our improved lock in its application to the usual hinged frame-sections of a hand-bag.

Fig. 7 is a detail sectional view showing the application of a key to our improved lock.

Having reference to the accompanying drawing, wherein similar reference-numerals denote like parts throughout the several views, we provide, in carrying out our present invention, a general housing formed from metal in suitable sheet-form, and consisting by preference of a base 2, top segment 2', front wall 3 and opposite end-walls 4, 4'.

A centering-spindle 3' is firmly secured at its lower end to the base 2, and at such a point therealong as to rise fixedly therefrom centrally within the housing aforesaid.

5 is an operating-bolt, centered in its vertical movements by means of the centering-spindle 3', though indirectly so in this instance, as will be later explained; and 5' is an evener, correspondingly centered in its vertical movements and underlying medially and acting as a unit with, the bolt aforesaid.

The bolt 5 is fitted with opposite recesses 6, 6', freely occupied, respectively, by the opposite lugs 7, 7' with which the evener 5' is provided; and between the latter and, say, a suitable bridge-piece 8, there is interposed a main spring 8', said spring being preferably of the spiral type, encircling the centering-spindle aforesaid, and serving the dual purposes of exerting without interruption a yielding stress both downwardly on the bridge-piece aforesaid and upwardly, though indirectly in this instance through the medium of the evener 5', on the operating-bolt 5, whereby the latter is held yieldingly protracted under normal conditions.

The bolt 5 supports an independently operable catch 9', engagable with the tenon, as 10, of a hasp, as 10', under incessant control of a suitable resilient medium 11, preferably in the form of a spiral spring, and being best employed in duplicate at the opposite end-portions of said bolt, substantially as shown.

As here shown the bolt 5 embodies a

2
medial, horizontal section 11', merged into a somewhat depressed, lateral horizontal section 12, which, in turn, is merged, through the medium of a down-turned connecting section 12', into a returned horizontal terminal 13, underlying the depressed, lateral section aforesaid, the catch aforesaid, suitably elongated to this end, piercing and operating in said terminal and the member 10 12 thereabove jointly, and the resilient medium 11, when taking the form of a spiral spring, encircling said catch between the section 12 and the terminal 13, bearing at its lower end on the latter and at its upper end 15 on said catch, as through the medium of a collar 13' afforded thereby, and whereby the catch is held at all times yieldingly protracted.

14 is a hollow finger-piece rising upwardly 20 from the bolt 5 through and suitably beyond the top-plate 2' of the housing, and whereby said bolt may be depressed by finger-pressure applied thereto by the user, and against the normal stress of the main spring 8', said 25 finger-piece being fitted with a suitable key-hole, as 14', at its crown, while the medial section 11', of the bolt 5 is fitted with a suitable key-way 15, similar in form to the key-hole 14'.

30 We further provide an upright key-way finder, which comprises an enlarged medial segment 16, disposed to rotate between the medial section 11', of the bolt 5, and the evener 5' thereunder; a minor reduced extension 16', projecting downwardly through the evener 5' and freely engaging, telescopically, the centering-spindle 3' thereunder; and a main extension 16'', the latter projecting upwardly freely through the section 11' 35 and further upwardly and through the crown of the finger piece 14, substantially as shown.

Said key-way finder is provided with a longitudinal, laterally open, key-passage 17, 40 which extends from its upper exposed end continuously along its main extension 16'' and including its medial segment 16, and terminating approximately at the base of the latter.

50 Taking the construction as thus far described, it will be seen that depression of the finger-piece 14 will result in depression of the bolt 5, including the catch carried thereby, and whereby the latter may be released 55 from its engagement with the tenon of a co-operating hasp, as 10'; and which catch, being operable independently of said bolt, may be caused to snap into engagement with the tenon of such co-operating hasp, even 60 though said bolt be locked against depression, a feature which constitutes an important characteristic of our present invention.

An additional important characteristic of our present invention resides in the provision 65 of a novel bolt-locking medium, key-

operable or finger-operable at the option of the user, said medium consisting in this instance of a suitable tumbler 17', here shown as being slidable in the housing of the device, and fitted with a shoulder 18, or its equivalent, adapted to pass closely under some portion of the bolt 5, as, say, its depressed horizontal section 12, and upon the tumbler being duly manipulated, whereby the said bolt becomes locked against depression. 75

To the end that the tumbler 17' may be shifted or caused, indirectly through the medium of a key, as 18', to slide within or relatively to the housing of our improved lock, said tumbler is provided with a primary recess 19, adapted to receive the lug, as 19', of a suitable key, as 18', the latter having been inserted into the key-passage 17, (Fig. 3), and thereafter turned to occupy approximately the position it is shown as occupying 80 in Fig. 7; whereupon, sliding of the tumbler in one direction in the housing of our improved lock, and as for locking the bolt 5 against retraction as hereinbefore explained, is effected upon said key being further duly 85 turned, as will be readily understood, while reverse movement of said tumbler, as for unlocking said bolt, may be effected by reversely turning said key.

20 is a lug turned inwardly from the front 95 wall of the housing of the device, and projecting into an elongated opening 20', with which the tumbler 17' is provided, the material of said tumbler, at the upper edge of its said opening, having a notched formation, whereby is provided a detent 21, preferably V-shaped, approximately, and the point of which rides upwardly upon, across and downwardly beyond the adjacent lug 20, all under the resilient stress of the main spring 8', exerted downwardly on the feet 21' with which said tumbler is provided, and indirectly, in this instance, through the medium 100 of the bridge-piece 8, which spans the space between and bears downwardly on said feet, the tumbler aforesaid being duly shifted. 110

Reversal of the foregoing operation of the parts now under consideration, takes place upon the tumbler being reversely shifted; and to the end that any tendency to objectionable centering of the point of the detent 21 on the lug 20, may be obviated, it is best that the primary recess 19 be flanked by a secondary recess 22 for the reception, in its turn, of the lug 19' of the key made use 115 120 of, and for further shifting of the tumbler, as will be apparent.

When desired that the tumbler of our improved lock shall be finger-operable, the same may be of a length exceeding the dimension of the housing aforesaid, taken in line therewith, and in which housing the tumbler operates, said tumbler hence affording a finger-segment, as 22', protruding from such housing as by way of a suitable open- 125 130

ing 23 formed, say, in one end-wall thereof, all as clearly shown in Figs. 2 and 3 of the drawing. Or, the tumbler may be provided with an appropriate finger-button, as 23', 5 whose shank works within a suitable opening 24 formed, say, in the front wall of the housing of the lock.

It will be seen from the foregoing that the user, grasping either the finger-segment 22' 10 or finger-button 23', may, by finger-pressure, manipulate the tumbler of our improved lock in a manner to lock the bolt thereof against retraction; or, he may do this indirectly through the medium of a suitable key, as 15 hereinbefore explained.

In the event, therefore, that the user shall need to hastily close and lock the hand-bag to which our improved lock may be applied, and where the use of a key for such purpose 20 would entail, say, the loss of valuable time, the user promptly shifts, by finger-pressure, as hereinbefore explained, the tumbler aforesaid and then promptly closes the hinged frame-sections of the hand-bag; 25 whereupon the tenon of the hasp secured, as in common practice, to one of said frame-sections, snaps into engagement with its co-operating catch 9'; such action of the parts being permissible by reason of the 30 fact that said catch is operable independently of the bolt aforesaid, and which supports it, as hereinbefore explained. The hand-bag thus locked may be later unlocked, at the user's leisure, through the medium 35 of a key as above explained.

In the use of a key in connection with our improved lock, such key is inserted into the key-passage 17 in the usual manner, by way of the key-hole 14', said key-passage being 40 first brought into registry with said key-hole; said key is then passed downwardly along said key-passage through the medial section 11', by way of the key-way 15 formed therein, the key-way finder being 45 used to find said key-way whatever its position relative to the key-hole 14' may be; and the lug of the key, the latter being turned, being used for operating the tumbler 17', as 50 hereinbefore explained.

It will be seen that our improved lock is not only well adapted for the purposes for 55 which it is intended, but that the same may be modified to a considerable extent without material departure being made from the spirit and principle of our invention as set forth in and coming within the scope of the claims hereto appended.

We claim as our invention:

1. A hand-bag lock comprising suitable 60 lock-mechanism and a housing therefor, said lock-mechanism including an operating-bolt supporting an independently operable spring-controlled catch engageable with the tenon of a hasp.

2. A hand-bag lock comprising suitable

lock-mechanism and a housing therefor, said lock-mechanism including a bolt, a tumbler and a main spring, the latter interposed between said bolt and said tumbler and exerting at one and the same time a yielding 70 stress upwardly on the bolt and downwardly on the tumbler.

3. A hand-bag lock comprising suitable lock-mechanism and a housing therefor, said lock-mechanism including a bolt, a tumbler 75 fitted with feet, a bridge-piece positioned on said feet and a main spring, the latter interposed between said bolt and said bridge-piece and exerting at all times a yielding stress upwardly on the bolt and downwardly 80 on said tumbler, through the medium of said bridge-piece.

4. A hand-bag lock comprising suitable lock-mechanism and a housing therefor, the latter having an inturned lug, said lock- 85 mechanism including a spring-controlled tumbler having an opening into which projects the lug aforesaid and having a detent formed at one edge of its said opening, said detent co-operating with said lug. 90

5. A hand-bag lock comprising suitable lock-mechanism and a housing therefor, said housing having a lateral opening and said mechanism including a spring-controlled bolt and a shouldered tumbler, the latter 95 shiftable laterally within and relatively to said housing, to bring the shoulder thereof into and out of locking relation to said bolt, and having a finger-piece formed thereon, and lying in registry with the plane of 100 movement thereof, said finger-piece protruding from said housing by way of the lateral opening formed therein.

6. A hand-bag lock comprising suitable lock-mechanism and a housing therefor, said lock-mechanism including a bolt having a lateral, horizontal section and a returned horizontal terminal, the latter underlying the former; a catch engageable with a hasp, operating in said section and said terminal 105 jointly and fitted with a collar; and a resilient element, the latter positioned between said terminal and said collar and yieldingly controlling said catch.

7. A hand-bag lock comprising suitable 115 lock-mechanism and a housing therefor, the latter having a centering-spindle rising fixedly from the base thereof, said lock-mechanism including a spring-controlled bolt operating on said spindle and having a key- 120 way formed through its medial section; a depressible finger-piece rising from said medial section and having a key-hole formed in its crown; and a key-way finder, the latter telescopically engaging said centering-spindle, extending rotatably upwardly through said medial section to and into the crown of said finger-piece, and provided with a longitudinal key-passage, open at its top, and adapted, upon said key-finder being rotated, 125 130

to be brought into registry with said key-hole and with said key-way, respectively.

8. A hand-bag lock comprising suitable lock-mechanism and a housing therefor, said lock-mechanism including a bolt, a tumbler key-operable or finger-operable at the option of the user and whereby the bolt may be locked against retraction; and a main spring, said main spring simultaneously controlling said bolt and said tumbler, and the latter slidable laterally within and relatively to the housing.

9. For a hand-bag lock a tumbler comprising

ing a relatively thin, upright body fitted with uniformly flat feet, arranged in spaced relation each to the other, and provided with an elevated bolt-locking shoulder.

10. For a hand-bag lock, a tumbler comprising a flat, upright body having an opening formed therein with a detent at its upper edge, fitted with a bolt-locking shoulder at its upper portion, and further fitted with a plurality of recesses above said shoulder.

BRODIE J. RICHARDSON.
CLAIRES S. BARBER.
